CLAIM

The ornamental design for a flow meter, gauge and measuring instrument, as shown and described.

DESCRIPTION

FIG. 1 is an exploded top view of the flow meter, gauge and measuring instrument;

FIG. 2 is an exploded bottom view of the flow meter, gauge and measuring instrument;

FIG. 3 is a front view of the flow meter, gauge and measuring instrument;

FIG. 4 is a rear view of the flow meter, gauge and measuring instrument;

FIG. 5 is a top view of the flow meter, gauge and measuring instrument;

FIG. 6 is a bottom view of the flow meter, gauge and measuring instrument; and

FIG. 7 is a side view of the flow meter, gauge and measuring instrument.

FIG. 8 is a perspective view of the top, front and side of the flow meter, gauge and measuring instrument; and,

FIG. 9 is a perspective view of the bottom, front and side of the flow meter, gauge and measuring instrument.

The broken line showing of structural features is included for the purpose of illustrating non-claimed subject matter and forms no part of the claimed design.
